BUTTON SEWING MACHINE

Michael McCann, Ozone Park, N. Y., assignor to
 The Singer Manufacturing Company, Elizabeth,
 N. J., a corporation of New Jersey

Application March 15, 1935, Serial No. 11,233

7 Claims. (CL. 112—110)

This invention relates to sewing machines more particularly of the single-thread chain-stitch type adapted for the sewing of buttons to garments.

Single-thread chain-stitch button-sewing machines, as commonly constructed, comprise a reciprocating eye-pointed needle, a rotary looper, and a work-clamp having a lower cloth-supporting plate and upper presser-device including button-gripping jaws which are movable laterally toward and away from one another to grip and release the button, and vertically toward and away from the cloth-supporting plate to hold and release the cloth to which the button is to be attached.

Stitch-positioning means are commonly provided for relatively moving the needle and work-clamp during the sewing to distribute the stitches, as desired, in the holes in the button.

Machines for sewing on four-hole buttons with two independent groups of stitches, and without a connecting or cross-over stitch, as demanded by the clothing trade, have commonly been provided with a stop-motion device which acts to stop the machine at the completion of each of the two groups of stitches, so that the sewing thread may be severed at the completion of the first group of stitches as well as at the completion of the last group of stitches.

The severing of the sewing thread is commonly accomplished after the machine comes to rest, by the act of the operator in lifting the button-clamp which exerts a strain on the thread leading downwardly from the last stitch and around the looper and thence upwardly through the work and through the needle-eye and an appropriate thread-clamp or thread-tension device to the source of supply. The strain exerted on the thread by the operator in lifting the button-clamp breaks the thread at the under side of the work close to the last stitch, in a manner well known.

It is necessary in certain button-sewing operations to provide the lower cloth-supporting plate of the machine with work-positioning means. For example, in sewing a button to cloth with stitches which pass through a stay-button below the cloth, it is necessary to provide the cloth-supporting plate of the work-clamp with stay-button-positioning means which is usually in the form of a circular stay-button-receiving aperture or pocket. Again, in blind-stitching four-hole buttons to garments, the cloth-supporting plate of the work-clamp is commonly provided with a shoulder for properly positioning a fold of ma-

terial to receive the button-fastening stitches which are caused to pass alternately through the fold and outside the fold, in a manner well known.

Difficulty has been experienced in the operation of known machines of the types above indicated because of the fact that in lifting the upper or button-clamping member of the work-clamp to break the thread at the completion of the sewing of the first group of stitches, the stay-button or fold of cloth, as the case may be, is raised out of its pocket or separated from its positioning means on the lower cloth-supporting plate and is not properly and certainly re-engaged with the same when the button-clamp is lowered preparatory to the sewing of the second or final group of stitches. In other words, in prior machines of the type in question, the work, after having been initially placed in the work-clamp and partially stitched, is necessarily disturbed relatively to the work-clamping and positioning devices before it is finished. This premature disturbance of the work in the work-clamp is troublesome and requires the operator to exercise considerable care and attention to avoid the production of imperfect work.

The present invention has for an object to provide a sewing machine with a work-clamp which may be lifted to break the sewing thread at the completion of the first of two group-stitching operations, without disturbing the work relative to the work-positioning means customarily associated with the cloth-supporting part of the work-clamp.

Another object of the invention is to provide a button sewing machine having a work-clamp including a lower cloth-support and upper button-gripping jaws with means permitting the lower cloth-support to move vertically with the button-gripping jaws as the latter are raised by the operator to break the thread at the end of the first group-stitching operation on a four-hole button, and preventing the cloth-plate from moving vertically with the button-gripping jaws in breaking the thread at the end of the second or final group-stitching operation.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

- Broadly speaking, the invention, in one aspect thereof, comprises the provision of a sewing machine with a work-clamp including separable work-clamping members which in one stop-position of the parts are movable simultaneously away from the machine bed without disturbing their relative work-clamping relations, and in another stop-position of the parts are relatively separable for removal and insertion of work.
- 10 In the accompanying drawings, Fig. 1 is a side elevation of a button-sewing machine embodying the invention. Fig. 2 is a section on the line 2—2, Fig. 1, Fig. 3 is a horizontal sectional view through the overhanging bracket-arm of the machine, 15 showing the mechanism for vibrating the needle-bar. Fig. 4 is a horizontal section through the bracket-arm standard showing the machine bed and the lower work-clamping plate in locked position on the machine bed. Fig. 5 is a section on the line 5—5, Fig. 4. Fig. 6 is a section on the line 6—6, Fig. 1. Fig. 7 is a view similar to Fig. 4, but on a larger scale, showing the lower work-clamping plate in unlocked position on the machine-bed. Fig. 8 is a plan view of the work-supporting 20 end of the lower work-clamping plate with the work-positioning means broken away. Fig. 9 is a front end elevation of the machine.
- Figs. 10 and 11 are views showing details of the stop-mechanism of the machine. Fig. 12 is 25 a section on the line 12—12, Fig. 7. Fig. 13 is a similar view on the line 13—13, Fig. 4. Fig. 14 is a view of the lower work-clamping plate locking device on the line 14—14, Fig. 4. Figs. 15 and 16 are transverse sectional views through the work-clamp at the sewing point at the respective times when the button-clamp is raised to break the sewing thread at the completion of the first group and second group of stitches in sewing on a four-hole button with an under stay-button. Fig. 17 30 is a section on the line 17—17, Fig. 16. Figs. 18 and 19 are transverse sectional views through the work-clamp at the sewing point at the respective times when the button-clamp is raised to break the thread at the completion of the first group and second group of stitches in blind-stitching a 35 four-hole button to a folded edge of material.
- The machine is constructed with a frame including the bed 1 from which rises the standard 2 of the overhanging bracket-arm 3 terminating 40 in the head 4. The bed 1 includes the extension 1^a of reduced width constituting a work-supporting arm.
- The stitch-forming mechanism is constructed substantially in accordance with the disclosure of 45 U. S. Patent No. 1,606,173, of Nov. 9, 1926, and comprises the endwise reciprocatory and laterally vibratory needle 5 and rotary non-threaded or wing-type looper 6 actuated in any known manner. The needle 5 is carried by the needle-bar 50 7 which is given its endwise reciprocatory movements by means of the usual link-connection 8 with the vibratory arm 9 fixed to the rock-shaft 10 actuated by the pitman-connection 11 from the eccentric 12 on the main shaft 13.
- 55 The needle-bar is guided in its reciprocatory movements by the upper and lower bearing blocks 14 and 15. The upper bearing block 14 is fixed to the pivot-shaft 16 which is journaled in the head 4. The lower bearing block 15 is fixed to the pivot-shaft 17 which is carried by the needle-bar-vibrating lever 18 fulcrumed on the adjustable fulcrum-block 19 and carrying a follower 20 entering the cam-groove 21 in the needle-bar-vibrating cam 22 on the slow vertical feed-shaft 23. The feed-shaft 23 makes one complete rota-

tion per complete button-sewing period (two group-stitching operations on a four-hole button) and is driven by the worm-and-gear connection 24 with the main-shaft 13.

Stationarily mounted on the bed-extension 1^a of the machine is the throat-plate 25 having therein the needle-slot 26.

The bed of the machine is provided with a pair of spaced guide-blocks 27 to slidably confine the work-clamp carrier-bar 28 having at one end a T-head 29 which is slotted at 30 and is formed with supporting lugs 31, 31 for the pivot-pin 32 on which are pivoted for movement independently of one another the shanks 33, 34 of the upper button-clamp and lower work-supporting and positioning means.

The shank 34 has rigidly fixed thereto a plate 35 the downwardly and forwardly offset portion 36 of which normally rests in sewing position upon the throat-plate 25 and bed-plate 37. This lower plate 35, 36 has pivotally mounted thereon at 38, and constituting a part thereof, a work-positioning plate 39 having at one end a circular stay-button-receiving pocket 40 and at its other end a block 41 having spaced work-positioning shoulders 42 and an intervening needle-clearance notch 43. The plate 39 may be turned end-for-end about its pivot 38 to position either the stay-button-receiving pocket 40 or the blind-stitch guide-shoulders 42 in sewing position. This lower work-positioning device is constructed substantially in accordance with the disclosure of U. S. Patent No. 1,998,587, dated Apr. 23, 1935. The plate 36 is formed at its forward end with a square sewing aperture 44, Fig. 35 8, exposing the needle-slot 26 in the throat-plate 25. The shank 33 carries the usual presser-device including the upper plate or bar 45 on which are mounted the usual reciprocally movable button-gripping levers 46 the construction 40 and function of which are well understood by those skilled in the art. In the present instance, the upper bar 45 of the work-clamp which carries the button-gripping levers 46 is spring connected to the lower or fabric-supporting bar 35, 45 36 of the work-clamp, so that when the upper bar 45 is lifted by the operator to break the thread at the end of the sewing of a group of stitches, the spring connection will yieldingly tend to lift the lower bar 35, 36 with it. To 50 this end a post 47 is anchored to the lower bar 35 and projects upwardly through a hole 48 in the upper bar 45. The post 47 is surrounded above the bar 45 by a compression spring 49 backed by an adjustable nut 50 threaded on the post 47. The bar 45 is lifted in the usual manner by the chain 51 connecting the bar 45 to the arm 52 on the rock-shaft 53 which also has fixed thereto an arm 54 connected to a treadle-operated pull-rod 55.

The upper bar 45 is yieldingly depressed to press or clamp the fabric upon the lower plate 36 by means of the plunger 56 bearing at its lower end upon the bar 45 and slidably mounted 65 in bearings 57, 58 in the arm 3. A spring 59 received in an axial bore in the plunger 56 and backed by an adjustable thumb-screw 60 exerts the desired fabric-clamping pressure upon the upper clamping bar 45. A collar 61 normally 70 loose on the plunger 59 may be tightened to hold the plunger 56 raised above and clear of the bar 45 in assembling or disassembling the parts of the work-clamp.

Sliding movements are imparted to the car- 75

Operation

rier bar 28 to shift the work-clamp longitudinally of the bed-extension 37 and relative to the needle 51 between group-stitching operations. To this end, there is adjustably mounted in the slot 50 in the head of the slide-bar 28 a roller-stud 30 which enters the longitudinally slotted arm 62 which enters the longitudinally slotted arm 63 of a bell-crank lever 63, 64 fulcrumed at 65 on the bed 1. The bell-crank lever-arm 64 has a follower 66 which enters the cam-groove 67 in the disk 68 on the slow shaft 23. The cam-groove 67 has two concentric semi-circular portions joined by the diametrically opposed eccentric portions or throws 69 which shift the work-clamp at the close of each group-stitching operation just before the machine comes to rest.

The machine is equipped with a stop-motion device of known construction such, for example, as that disclosed in U. S. Patent No. 1,983,555, of Dec. 11, 1934. Such a stop-motion device 20 comprises a power-receiving belt-pulley 10 which is loose on the mainshaft 13 and is movable endwise of the latter to carry a driving stud 71 on the side of the pulley 10 into and out of driving engagement with an arm 72 fast on the main shaft 13. The position of the pulley 10 lengthwise of the main shaft 13 is controlled by the inclined head 73 of an arm 74 fixed on the stop-motion control rock-shaft 75 biased by a coil-spring 76 to turn the rock-shaft 75 to the stop-position shown in Fig. 1, in which position the inclined head 73 working in the grooved hub 77 of the pulley 10 has shifted the latter so that the stud 71 is out of driving engagement with the arm 72 on the main shaft 13. The rock-shaft 75 has fixed to it a collar 78 formed with a shoulder 79 which is engaged by a spring-biased latch 80 fulcrumed at 81 and rigidly associated with a trip-arm 82 in position to be engaged by the diametrically opposed tripping points 83 on the slow-shaft 23. The latch 80 40 detains the rock-shaft 75 in machine-running position and, when shifted by one of the tripping points 83, releases the rock-shaft 75 which springs to machine-stopping position, Fig. 1. 45 Since there are two tripping points 83 on the slow-shaft 23, the machine will perform two group-stitching operations per complete cycle, the machine being stopped automatically at the completion of each group of stitches. The customary treadle-connection, not shown, is used 50 to rock the shaft 75 to machine-running position.

Pivottally mounted at 84 on the machine bed, 55 is a latch 85 having a nose 86 which, at the rearward sewing position of the work-clamp, Fig. 4, overlies the corner 87 of the lower clamp-plate extension 36 adjacent the latch-clearance notch 88 therein, and locks the clamp-plate 35, 36 to 60 the bed 1 so that it will not be lifted with the upper button-clamp-supporting arm 45 when the latter is lifted at the completion of a group of stitches. In the forward sewing position of the work-clamp, Fig. 7, the corner 87 of the lower 65 clamp-plate is clear of the latch nose 86 and hence the lower clamp-plate 35, 36 is free to rise with the button-clamp-supporting arm 45; all parts of the work-clamp rising as a unit and without relative disturbance of any of the button and cloth-positioning and clamping elements.

The latch 85 is backed by a spring 89 which 70 rigidly retains the latch in normal position with its adjustable abutment screw 90 in engagement with one of the work-clamp guide-bars 27.

In sewing a four-hole button 91 with a stay-button 92 to a body-fabric 93, Figs. 15 and 16, by two parallel groups of stitches s¹, s², Fig. 7, and without a diagonal cross-over stitch, the operator places the stay-button 92 in the stay-button-positioning pocket 40 in the guide-plate 39 on the lower clamp-plate 36 which is locked in its lower rearward position upon the throat-plate 25 by the latch 86, as shown in Fig. 4. The main button 91 is inserted in the jaws of the button-gripping levers 46 which are lowered with the button 91 into clamping relation with the body-fabric 93 upon the lower work-positioning plate 39 which constitutes a part of the lower clamp-plate 36. 15

The machine is then started and the needle 5 sews the first group s¹ of stitches through the forwardly disposed pairs of holes in the two 20 buttons 91, 92. The needle-bar-vibrating cam 21 is so cut that the needle makes its last three complete reciprocations through the same holes in the main and stay-buttons without making any lateral movement and thus causes the usual 25 final knot tying stitches to be formed. After the needle has risen from the work at the completion of the last stitch, one of the throws 69 in the cam 61 shifts the work-clamp forwardly to the position shown in Fig. 7, whereupon one of the 30 stop-motion tripping points 83 releases the stop-motion control rock-shaft 75 and stops the machine.

Just before the machine is stopped one of the rounded knobs 94 on the cam-disk 22 rides under 35 and lifts the lever 95 which acts upon the thread-tension device 96 to heavily tension the sewing thread in the usual manner for the thread breaking operation.

Thus, when the machine comes to rest at the 40 completion of the first group s¹ of stitches, the work-clamp is in the position shown in Fig. 7, in which the corner 87 of the lower clamp-plate 36 is clear of the latch 86.

When the operator exerts a pull upon the rod 45 55 to raise the button-clamp 45, 46 for the usual thread-breaking operation, the lower clamp-plate 36 and stay-button-positioning plate 39 carried thereby are free to rise with the work, as shown in Fig. 15, without any disarrangement of 50 the relative positions of any of the work-clamping elements. The stay-button 92 is not lifted out of its pocket 40 at this incomplete stage of the button-sewing operation and the work-clamp may be instantly lowered and the machine re-started without a moment's delay and without 55 the necessity of the exercise of any particular care on the part of the operator.

At the completion of the sewing of the second or final group s² of stitches, including the usual 60 knot-tying stitches, the work-clamp is returned to the position shown in Fig. 4, just before the stop-motion control rock-shaft 75 is released by the other of the two tripping points 83. In this position of the work-clamp the corner 87 of 65 the lower clamp-plate 36 has passed under the latch 86 and the lower clamp-plate 36 and stay-button positioning plate 39 are thus locked against rising from the bed 1, Fig. 16, when the button-clamp levers 46 are raised by the operator 70 to break the thread and open the work-clamp for removal of the finished work.

The operations are the same in blind sewing a four-hole button 97, Figs. 18 and 19, to a fold-edge 98 of fabric. To properly position the fold- 75

edge 98, it is customary to turn the work-positioning plate 39 end-for-end to bring the fold-edge-positioning shoulders 42 into operative position above the sewing aperture 44 in the lower clamp-plate 36. At the completion of the first group s' of stitches, Fig. 18, the work-clamp is raised to break the thread and, in this operation, there is no disturbance of the fold-edge 98 relative to the fold-edge-positioning shoulders 42 and usual fabric-clamping foot 98'; all parts of the work-clamp being raised as a unit. After the final group s^2 of stitches has been formed, only the button-gripping levers 46 are raised, Fig. 19, to break the thread and release the fabric for removal from the machine.

The usual vibratory thread-catcher 89, having the thread-catching pocket 100, Fig. 17, is preferably used to pull the broken needle-thread-end 101 out of the work and releasably detain it to one side of the sewing point for the beginning of the ensuing group-stitching operation. This device is mounted on the clamp-lifting rock-shaft 53.

Should an operator lift the work-clamp prematurely, when the lower plate 36 is in unlocked position, Fig. 7, and before the work-clamp has been automatically shifted to the locked position shown in Fig. 4, there is danger that the corner 81 may clash with the latch-nose 86. To avoid breakage of the parts under this condition, the latch 85 is pivotally mounted and backed by the spring 89 which permits the latch-nose 86 to yield rearwardly horizontally, should it be struck by the prematurely raised corner 81. The latch-nose 86 is beveled at 86' so that the corner 81 may, if prematurely raised above the latch nose 86 and subsequently lowered, engage the beveled face 86' in its vertically downward movement and snap past the latch-nose 86 to the initial position of the parts shown in Fig. 4.

The invention is not to be understood as limited to the details of construction and relative arrangements of parts shown and described, as such details and relative arrangements may obviously be variously modified by those skilled in the art within the spirit of the invention.

Having thus set forth the nature of the invention, what I claim herein is:—

1. In a sewing machine, stitch-forming mechanism including a reciprocating needle, opposed work-clamping members, means yieldingly urging said clamping members into work-clamping position, means for relatively shifting said needle and work-clamping members crosswise of the path of needle-reciprocation, lifting means connected to one of said clamping members and effective to raise said members as a unit in one of the relatively laterally shifted positions of said needle and clamping members, and means restraining one of said clamping members against responding to the action of said lifting means in another relative position of said needle and clamping members.

2. A button sewing machine having, in combination, stitch-forming mechanism including a reciprocating needle, a work-clamp including a vertically movable cloth-support and button-gripping jaws movable toward and away from said cloth-support, means for relatively moving said needle and work-clamp to sew two independent groups of stitches in a four-hole button, a stop-motion device arranged to stop the machine at the completion of each of said groups of stitches, and manually operated means for lifting the button-gripping jaws to break the sewing thread,

yielding means connecting the button-gripping jaws with the cloth-support to lift the latter with said jaws, and a device for locking the cloth-support against vertical movement in alternate group-stitching operations.

3. In a button-sewing machine, the combination with the machine bed and a feed-cam-actuated member, of a work-support pivoted on said member for upward movement away from normal sewing position on the machine bed, a button-clamp also pivoted on said member, a spring-connection between said work-support and button-clamp, means for lifting said button-clamp, and means controlled by movement of said feed-cam-actuated member for alternately locking and unlocking said work-support in normal sewing position on said machine bed.

4. A button-sewing machine having, in combination, a frame including a bed, stitch-forming mechanism including an endwise reciprocating and laterally vibratory needle, a work-clamp including lower work-supporting and positioning means and upper button-gripping jaws, means for shifting the work-clamp from one sewing position on said bed to another to successively present the two pairs of holes in a four-hole button to said needle for the sewing therein of two independent groups of stitches, means for simultaneously lifting the button-gripping jaws and lower work-supporting and positioning means from said bed to break the thread at the completion of the first group of stitches, and means for retaining the lower work-supporting and positioning means in normal sewing position when the button-gripping jaws are lifted at the completion of the second group of stitches to break the thread.

5. A button-sewing machine having a frame including a bed, stitch-forming mechanism including a reciprocating needle, a work-clamp including a lower work-supporting plate and an upper button-holder each pivotally carried by said bed and each pivotally movable independently of the other, manually operated means for lifting said button-holder, spring means connected to said button-holder for lifting said lower plate from said bed, and hold-down means on said bed for at times retaining said lower plate on said bed when said button-holder is lifted.

6. In a work-clamp for sewing machines, a bed, upper and lower work-clamping members on said bed, manually operated means to lift the upper clamping member, spring means connected to the upper clamping member to yieldingly lift the lower clamping member, and unyielding means for at times retaining the lower clamping member in normal position on said bed when the upper clamping member is lifted.

7. A sewing machine having, in combination, stitch-forming mechanism including a reciprocating needle, a work-clamp including a lower clamp member and an upper clamp member movable toward and away from said lower clamp member, means for relatively moving said needle and work-clamp to sew two differently located groups of stitches in the work, a stop-motion device arranged to stop the machine at the completion of each of said groups of stitches, and manually operated means to simultaneously lift and simultaneously lower both clamp members at the close of the first group-stitching operation and to lift and lower the upper clamp member only, at the close of the following group-stitching operation.
